ATTORNEY.

UNITED STATES PATENT OFFICE

HARRY F. HUSTED, OF WINCHESTER, VIRGINIA, ASSIGNOR TO LAWRENCE W. SCOTT,
OF WYOMING, PENNSYLVANIA

CIGARETTE AND CIGAR HOLDER

Application filed January 18, 1928. Serial No. 247,666.

This invention relates to a cigarette or cigar holder and has for its object to provide, in a manner as hereinafter set forth, an article of such class including means for conveniently securing and releasing a cigarette or cigar to and from the holder when occasion requires, and further with said means acting as an air-tight seal around the cigar or cigarette at the outer end of the holder thereby providing solely for the intake of the air through the cigarette or cigar when smoking. Further objects of the invention are to provide, in a manner as hereinafter set forth, a cigarette or cigar holder for the purpose referred to and which is simple in its construction and arrangement, strong, durable, compact, pleasing in appearance, thoroughly efficient in its use, readily assembled, and comparatively inexpensive to manufacture. With the foregoing and other objects in view the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope of the claims hereunto appended. In the drawings wherein like reference characters denote corresponding parts throughout the several views:

Figure 1 is a longitudinal sectional view of a cigarette or cigar holder in accordance with this invention and with the sections thereof connected together and in position to secure the cigar or cigarette to the holder.

Figure 2 is a side elevation of the holder.

Figure 3 is an end view thereof.

Figure 4 is a section on line 4—4 Figure 1.

Figure 5 is a section on line 5—5 Figure 1.

Figure 6 is a perspective view disassembled of the combined clamping and sealing section of the holder.

Figure 7 is a longitudinal sectional view

of a modified form of combined clamping and sealing section.

A holder in accordance with this invention, includes a carrier section and a combined clamping and sealing section adjustably connected to the former and which detachably connects the cigar or cigarette to the holder and also seals the outer end of the latter.

Referring to Figures 1 to 6 of the drawings the holder includes a rigid, tubular mouthpiece 1 constituting the carrier section of the holder and is formed of a unitary body of any suitable material. The carrier section is tubular and formed of portions of different inner diameters. The said portions of different inner diameters are indicated at 2, 3, 4, 5 and 6. The carrier section has a reduced inner portion 7 providing the mouth end thereof and which is peripherally shouldered as at 8. The portion 2 is of greatest inner diameter, the portion 3 slightly less in diameter than the portion 2, the portion 4 of less diameter than the portion 3, the portion 5 of less diameter than the portion 4 and the portion 6 of less diameter than the portion 5. The portion 6 is of greater length than any of the portions 2, 3, 4 and 5 and provides a smoke passage. The portion 3, which is interposed between the portions 2 and 4 is provided with threads throughout as indicated at 9. The portions 4, 5 and 6 communicate with each other. The portion 3 is closed to the portion 4 and to the portion 2, when the sections are connected together.

The combined clamping and sealing section has a part thereof arranged within the carrier section and is extended into the latter from the outer end thereof. The combined clamping and sealing section is referred to generally at 10 and is of tubular form. The section 10 includes an outer part 11, an intermediate part 12 and an inner part 13. The part 11 is of greater diameter than the part 13 and the part 12 gradually decreases in diameter.

ter from the part 11 to the part 13. The part 12 is of tapered contour. The section 10 is formed with a plurality of lengthwise extending slits, as shown four in number, but this number can be increased or diminished if desired. The inner end of each slit is arranged intermediate the ends of the inner portion 13 and the outer end arranged at the outer end of the portion 11.

10 Each of the slits is indicated at 14 and tapers in opposite directions substantially from its center towards each end whereby each edge of each slit will be formed intermediate its ends with a point. The point of one edge 15 of a slit opposes and is arranged in close proximity to the point on the other edge of the slit. The points on the edges of each slit coact to provide a seal for a purpose to be presently referred to. The points on the edges of 20 the slits are arranged where the part 11 merges into part 12. The parts 11 and 12 provide a clamp for a cigar or cigarette to detachably secure it to the carrier, as when section 10 is screwed inwardly with respect to 25 the carrier section 1, the outer end of the latter riding against part 12 will contract parts 11 and 12 to clamping position thereby detachably securing the cigarette with the carrier section, and at the same time the points on 30 the edges of the slits will abut to provide a seal to prevent the passage of air to the inner portions of the slits and also prevent the passage of air between the periphery of the cigar or cigarette and inner face of part 12.

35 To facilitate the entrance of a cigar or cigarette into part 11, the outer end of the latter is flared as indicated at 15.

Secured upon the non-slitted portion of the inner part 13 is a peripherally threaded 40 sleeve 16 which has threaded engagement with the threads 9 for the purpose of securing section 10 to the carrier section. The securing in of the section 10, with respect to the carrier section, will provide for the outer end 45 of the carrier section to ride against the part 12 of section 10 for the purpose of shifting the slitted portions of sections 10 together so that the cigar or cigarette will be tightly clamped and held by the holder. When the 50 section 10 is unscrewed so as to shift outwardly the cigarette or cigar will be released and can drop from the holder and it does not necessitate the operator to catch hold of the cigarette or cigar, as all the operator need do 55 is to grasp the outer portion of the part 11 and turn it in the desired direction for the purpose of releasing the cigar or cigarette therefrom.

To prevent the entrance of air into the carrier section by passing between the outer face 60 of the section 10 and the inner face of the carrier section a collet or ring 16' is employed and which has its inner face, as at 17 beveled for seating upon the tapered intermediate 65 part 12. When the section 10 is screwed in-

wardly the collet or ring 16' will engage the outer end edge of the carrier section and bind on the part 12 of the section 10 and provide an air tight seal to prevent entrance of air. Furthermore, in case that the threads 9 or the threads on the sleeve 16 are irregularly worn 70 the collet 16' will act as a centering means for the section 10 and seal at the outer end of the carrier section.

The form shown in Figure 7 is the same as that heretofore referred to, with this exception that the sleeve 16 is omitted and the inner part of the clamping section and which is indicated at 18 has a thickened portion 19 provided with peripheral threads 20 which perform the same function as the peripheral threads on the sleeve 16. The intermediate part of the clamping section, in Figure 7, is indicated at 21 and the outer part at 22. Otherwise than that as stated the clamping section shown in Figure 7 is constructed in the same manner as the clamping section shown in Figures 1 and 6. The collet or ring 16' is employed in connection with the form shown in Figure 7.

It is thought the many advantages of a cigarette and cigar holder, in accordance with this invention, can be readily understood, and although the preferred embodiment of the invention is as illustrated and described, yet it is to be understood that changes in the details of construction can be had which fall within the scope of the invention as claimed.

What I claim is:

1. A holder for the purpose set forth comprising a carrier section and a combined clamping and sealing section extending into and threadedly engaging with the carrier section, said combined clamping and sealing section provided with one or more slits extending lengthwise thereof, each of said slits tapering in opposite directions approximately from the center thereof to each end to provide each of the edges of the slits, intermediate its ends with a point, said combined clamping and sealing section including an intermediate tapered portion coacting with the carrier section to provide for the abutting of the points of each slit to seal the inner portion of the slit to the outer portion thereof and further to contract the clamping section to detachably secure a cigar or cigarette with the carrier section.

2. A holder for the purpose set forth comprising a carrier section and a combined clamping and sealing section extending into and threadedly engaging with the carrier section, said combined clamping and sealing section provided with one or more slits extending lengthwise thereof, each of said slits tapering in opposite directions approximately from the center thereof to each end to provide each of the edges of the slits, intermediate its ends with a point, said combined clamping and sealing section including an
